UNITED STATES PATENT OFFICE.

HENRY O'B. HARDING, OF MINNEAPOLIS, MINNESOTA, ASSIGNOR TO WASHBURN-CROSBY COMPANY, OF MINNEAPOLIS, MINNESOTA, A CORPORATION OF MINNESOTA.

FLOUR-PACKING MACHINE.

Application filed June 1, 1920. Serial No. 385,565.

To all whom it may concern:

Be it known that I, HENRY O'B. HARDING, a citizen of the United States, residing at Minneapolis, in the county of Hennepin and State of Minnesota, have invented certain new and useful Improvements in Flour-Packing Machines, of which the following is a specification.

The present invention relates to machines for packing materials in pulverulent form, and more particularly for the packing of flour in bags or small sacks.

The object of the invention is the provision of a machine of the character stated the construction of which is such as to enable bags or sacks of varying sizes, and designed to contain varying weights of the material packed, to be filled expeditiously and without the necessity for incorporating weighing instrumentalities in the machine for determination of the precise weight of the filled containers.

The invention further seeks to provide a machine of the class referred to wherein provision is made for compacting the material as it enters the bag or sack so as to fill the latter completely, and thus insure the proper weight of the contents which the bag or sack is intended to contain.

Furthermore, the invention also aims to provide a packing machine such as mentioned the parts of which are so organized and related as to preclude undue impairment thereof, thereby affording a machine requiring but minimum attention to maintain in proper working condition, and one in which the necessity for repair or replacement of parts is comparatively slight.

Further objects and advantages will appear as the nature of the improvements is better understood, the invention consisting substantially in the novel construction, combination and arrangement of parts herein-after fully described, illustrated in the accompanying drawings and finally pointed out in the appended claims.

A practical embodiment of the invention is presented in the disclosure herein, but this is not to be taken in a limiting or restrictive sense, it being intended to delineate to the art an appropriation of the concept and its application in practical form to the purposes for which the invention is contemplated.

In the drawings—

Fig. 1 is a front elevation of a flour packing machine constructed in accordance with the present invention;

Figs. 2 and 3 are side and rear elevations, respectively, thereof;

Fig. 4 is a sectional plan view on the line 4—4, of Fig. 1;

Fig. 5 is a vertical transverse sectional view of the bag-supporting carriage;

Fig. 6 is a front elevation thereof;

Fig. 7 is a detail sectional view on the line 7—7, of Fig. 3;

Fig. 8 is a detail elevation of the accelerating clutch-shifting lever and the actuator therefor;

Fig. 9 is a longitudinal sectional view of the accelerating clutch;

Fig. 10 is a detail perspective view of certain of the lever-shifting contacts and the support for the same;

Fig. 11 is a similar view of the counterbalance for the bag-supporting carriage.

Referring now in detail to the accompanying drawings, the numeral 10 designates a pair of vertical supporting standards 80 which form a part of the machine frame, and by which the weight of the machine is sustained. Arranged between said standards 10, and suitably held therein, is a feed hopper 11 with which communicates a supply chute 12 that leads from an elevated source of the flour to be packed. The passage of the flour through the chute 12 is controlled by a sliding gate 13 arranged therein, and connected to said gate 13 is 90 an operating lever 14 which has a lug 15 connected thereto that cooperates with a supporting rack 16 projecting to one side of the frame of the machine. The teeth of the rack 16 are engaged by the lug 15, and obviously the degree of movement of the gate 13 across the supply chute 12 may be easily controlled and regulated by adjustment of the operating lever 14 on said supporting rack.

At the head of the supporting standards 10, and disposed at opposite sides of the frame, is a pair of horizontal supporting rails 17, which rails preferably are formed of angle iron, and passing through the chute 12, in parallel relation with the rails 17, but at a point above the same, is a line shaft 18 from which power is derived for driving

the machine. This shaft may be operated from any suitable source, and where it is desired to utilize a battery of the machines herein described the same may be arranged 5 in line, and the shaft 18 will provide a common source of power for their operation.

A worm gearing 19, conventionally illustrated and of suitable construction, is arranged at one side of the chute 12 and serves 10 to transmit power from the shaft 18 to an intermediate shaft 20 the ends of which are journaled in suitable bearings 21 carried by the supporting rails 17. At the opposite side of the supply chute 12, and located at 15 the upper portion of the machine frame, is a clutch mechanism 22 which is connected to a packing shaft 23 disposed vertically of the machine, said clutch mechanism 22 providing an intermediate driving connection 20 between the packing shaft 23 and the line shaft 18. The shaft 23 passes downwardly through the feed hopper 11, and mounted on said shaft, within said hopper 11, is a plurality of packing augers 24. These 25 augers serve to force the flour or other material being packed downwardly through the hopper 11, which hopper has a contracted tapering lower end 25 which terminates in a discharge nozzle 26. The bag to be filled 30 is applied to the lower end of the discharge nozzle 26, and under the action of the packing augers 24 the flour is compactly pressed into the container on said nozzle.

Cooperating with the feed hopper 11 and 35 its discharge nozzle 26, and serving to support the bag in sustained relation to the nozzle 26 as the bag is being filled, is a bag supporting carriage 27. This is in the form of a rectangular vertically-disposed frame 40 28 from which extends a horizontally-arranged shelf 29, said carriage 27 being mounted for vertical movement between the supporting members 10 of the frame. The edges of the frame 28 are fitted between vertical guide rods 30, a pair of which is mounted at the inner face of each of the members 10. The frame 28 has a series of rollers 31 mounted thereon, said rollers being disposed 45 between the guide rods 30, and thereby reducing frictional movement as the carriage 27 operates. There is slight play between the rollers 31 and the guide rods 30 to accommodate proper vertical movement of the frame 28 so as to insure rolling contact of 50 said rollers with the guide rods in such movement of the frame. This provides for slight canting of the frame 28 as it rises and falls and establishes proper movement of the rollers 31 along the guide rods 30.

60 A controlling shaft 32 is arranged at the rear of the supporting members 10, the ends thereof being mounted in suitable bearings 33 carried by said members 10, and mounted on said shaft 32 is a sprocket wheel 34 over 65 which a sprocket chain 35 is connected to a

brace strap 36 which extends from the shelf 29 to the upper end of the frame 28 and thereby imparts rigidity to the bag-support 27, the other end of said chain 35 being connected to a supporting frame 37 designed 70 to receive a plurality of counterweights 38 for counterbalancing the carriage 27. The frame 37 is received by a pair of parallel vertical guides 39 suitably supported by straps 40 on the members 10. Provision, 75 therefore, is made for counterbalancing the carriage 27, and when the latter is relieved of the weight of the filled bag the weights 38 serve to elevate the shelf 29 of said carriage to a point immediately below the discharge nozzle 26, and to maintain the same in this position so that the empty bag placed upon the discharge nozzle 26 will be held thereon until forced downwardly by the introduction of the flour from said nozzle. The ends of the counterweights 38 are notched 80 for receiving inwardly-extending V-shaped guides 41 arranged vertically of the sides of the frame 37. These guides terminate short of the upper end of the frame 37 to 85 permit introduction of the weights to and removal of the same from the frame. When placed over the upper ends of the guides 41 the notches of the weights 38 register with the upper ends of said guides, and their downward movement in the frame 37 locks them in engagement with said guides. At the upper end of the frame 37, and arranged at opposite sides thereof, is a pair of pivoted 90 latch members 42 which are mounted upon a pintle 43. Each of these latch members may be swung independently of the other, their lower ends extending below the upper end of the frame 37, and thus preventing 95 any displacement of the counterweights 38 from the guides 41 until the latch members are properly swung to one side of the frame.

For starting the packing shaft 23 and the augers carried thereby an operating lever 44 is employed. This is in the form of a bell-crank lever which is bolted to a shaft 45 carried by one of the supporting members 10. The short arm of said bell-crank lever is pivoted to a connecting rod 46 which extends upwardly, the upper end of said rod 46 being pivotally connected, as at 47, to an actuating arm 48 which is connected to the clutch mechanism 22 and by which the driving relation of said clutch mechanism to the driving shaft 18 is controlled. The operating lever 44 may be controlled by hand or by foot, and for the latter purpose a treadle frame 49 is hingedly connected to the lower ends of the members 10, a connecting link 50 extending from said frame 49 upwardly to the operating lever 44. Thus it will be seen that if the foot be applied to the frame 49, and downward pressure be exerted thereon, the operating lever 44 will be swung downwardly, 125 130

exerting corresponding movement on the rod 46, and this so actuates the clutch mechanism 22 as to connect the shaft 18 with the packing shaft 23, thereby placing the latter in operation. This operation of the packing shaft continues so long as the connecting rod 46 is drawn downwardly. For actuating the rod 46 in the opposite direction, and breaking the driving connection between the shaft 23 and the shaft 18 through the clutch mechanism 22, a coil spring 51 is employed. The lower end of said spring 51 is connected to an attaching bracket 52 carried by the rod 46, while the upper end of said spring is suitably connected to the machine frame. In the downward movement of the rod 46 the spring 51 is placed under tension, and this tension serves to raise the rod 46 when pressure on either the lever 44 or the treadle frame 49 is released.

It will be understood that as the flour is forced into the container which has been positioned on the discharge nozzle 26, and is supported by the shelf 29, the counterweights 38 offer a certain resistance to the downward movement of the carriage 27. To properly compact the mass within the container it is desirable that upon introduction of the flour it shall meet with relatively high resistance as it enters the container. To provide for this a friction wheel 53 is mounted on one end of the shaft 32. Associated with said wheel 53 is a pair of oppositely disposed brake shoes 54 and 55, said shoes being connected to supporting arms 56 and 57, respectively. The upper ends of these supporting arms are connected to attaching brackets 58 and 59 arranged at one side of a supporting arm 60 that is suitably connected to the machine frame. The lower ends of the supporting arms 56 and 57 are provided with links 61 and 62, which links are connected to the opposite ends of an elongated head 63 carried by an actuating lever 64. This lever is pivoted, as at 65, to a fixed point on the machine frame, which pivot 65 serves as the fulcrum of said lever.

In order that the friction wheel 53 may be subjected to the braking action of the shoes 54 and 55 concurrently with the starting of the packing shaft 23, so that the required resistance may be offered to the introduction of the mass of flour into the container, a yoke 66 is hingedly connected to the lever 64, the head of said yoke having screw-threaded engagement with a rod 67 the lower end of which is provided with a head 68 which is positioned beneath an attaching bracket 69 carried by the rod 46, and through which bracket the rod 67 is adapted to slide. The screw-threaded connection between the rod 67 and the yoke 66 provides for relative adjustment of these

parts in order to lengthen or shorten the connection between said yoke and the attaching bracket 69. This is desirable in order to vary the throw of the lever 64 and the relative movement of the rod 46 with respect thereto. When the adjustment has been effected a locking thumb nut 70 serves to hold the rod 67 and the yoke 66 in adjusted relation by being tightened against said yoke. The rod 67 also may be conveniently rotated when effecting the adjustment noted by means of a wing nut 71 fixedly held thereon. Due to the employment of the yoke 66, the rod 67 and the attaching bracket 69, downward movement of the connecting rod 46 will cause the bracket 69 to engage the head 68 of said rod, and exert a downward pull on the lever 64 concurrently with the downward movement of the rod 46. This brings the brake shoes 54 and 55 into engagement with the friction wheel 53, and thereby retards rotation of said wheel as the carriage 27 is lowered in the bag filling operation. To release the shoes 54 and 55 from engagement with said wheel 53 a coil spring 72 is connected at one of its ends to the lever 64, the other end being suitably connected to the machine frame. Obviously, the spring 72 is placed under tension on the downward movement of the lever 64, and remains under tension so long as said lever is held in this lowered position. When, however, the connecting rod 46 moves upwardly, so as to relieve the pull exerted on the rod 67 and the yoke 66, the spring 72 exerts a pull on the lever 64, and this throws the brake shoes 54 and 55 away from the friction wheel 53.

A brake-setting lever 73 is also pivotally mounted on the inside of the machine frame (see Fig. 7) in proximity to the friction wheel 53, the forward end of said setting lever being bent outwardly and connected to the lever 64 by a link 74. The rear end of the lever 73 extends towards the control shaft 32 and its extremity is bent inwardly and projects into the path of movement of a tappet arm 75 carried by said shaft 32. The purpose and operation of this setting lever 73 and tappet arm 75 will presently appear.

In the filling of the bag, as before stated, the present invention contemplates the employment of bags of different sizes, and, therefore, different weights of the contents thereof. When the bags are filled to the required extent, and it is desired to permit removal of the same from the bag supporting carriage, it is proposed to accelerate the downward movement of said carriage so that the filled bag may be quickly moved from beneath the discharge nozzle 26 and a new empty container placed thereunder. To this end the control shaft 32 is provided

with an intermittent drive which is actuated from the constantly rotating shaft 20. This drive includes a pulley 76 carried by the shaft 20 over which is trained a belt 77, and said belt is also trained over a driven pulley 78 connected with one member 79 of a clutch, the other member 80 of which is fastened to the shaft 32. While the member 79 is supported by the shaft 32 it rotates independently thereof. When moved into engagement with the fixed member 80 the shaft 32 is actuated at the speed of the clutch member 79 and the driven pulley 78, and this speed is such as to accelerate rotation of the shaft 32, thereby causing the bag supporting carriage 27 to descend for the rest of its downward movement under a quick impulse, and thus increasing its speed over that induced by the introduction of the flour into the bag by the compressive action of the packing shaft 23 and its augers. The acceleration of the downward movement of the bag supporting carriage does not take place until the required weight of the contents has been filled in the bag. At this point the carriage 27 has descended to a sufficient extent that a downwardly-directed contact block 81 mounted thereon will engage a releasing lever 82 carried by the shaft 45, and thus connected, through the operating lever 44, with the rod 46. The lower end of the releasing lever 82 is offset so as to extend into the path of downward movement of the block 81. When the latter engages the releasing lever 82 it throws said lever 82 towards the member 10, or from the position shown by dotted lines in Fig. 1 to that shown by full lines therein, and this causes the rod 46 to move in an upward direction and thereby actuate the clutch mechanism 22 to brake its driving connection with the shaft 18, whereupon the packing shaft 23 ceases to rotate. It is at this time that the clutch member 79 is moved into engagement with the clutch member 80. To effect this it will be observed that the member 79 and the driven pulley 78 are mounted on a transversely swinging supporting bar 83 pivotally connected to a bracket 84 carried by one of the frame members 10. The lower end of the supporting bar 83 has a link connection 85 with a shifting lever 86 fulcrumed upon a support 87 carried by the machine frame. The lower end of the shifting lever 86 (see Fig. 8) is in the path of movement of a bell-crank lever 88 the vertical arm of which has a horizontal engaging foot 89 at its lower end against which the lower end of the lever 86 normally rests, and this engagement is preserved by a coil spring 90 one end of which is connected to the lever 86 and the other end of which is connected to a vertical supporting bar 91 carried by the machine frame and arranged centrally there-

of. The spring 90 exerts a pull on the lower end of the lever 86 to swing the latter towards the middle of the machine frame, and said bell-crank lever 88 is pivotally connected to an attaching arm 92 carried by one of the frame members 10. As the lower end of the lever 86 normally contacts with the bell-crank lever 88 the horizontal arm thereof is normally raised. Pivotally connected to the horizontal arm of said lever 88 is a contact finger 93 having an anti-friction roller 94 journaled thereon. The finger 93 may swing upon the bell-crank lever 88 in an upward direction, as indicated in the dotted lines in Fig. 8, but its movement in a downward direction is limited by a lug 95 which engages a shoulder 96 formed on the horizontal arm of the lever 88. The engagement of the lug 95 with the shoulder 96 maintains the finger 93 in alignment with said horizontal arm, and consequently pressure exerted on the contact finger 93 in a downward direction will swing the bell-crank lever 88 so that the foot 89 thereof will swing the lower end of the lever 86 outwardly, resulting in engagement of the clutch member 79 with the clutch member 80. This establishes driving connection between the pulley 78 and the shaft 32 and the accelerated downward movement of the bag supporting carriage results.

To effect actuation of the bell-crank 88 in the manner just described a contact shoe 97 is carried by the contact block 81, which block is elongated, as shown in Fig. 10, and said block 81 is adjustably mounted on a vertical slotted support 98 centrally arranged on the frame 28 of the carriage 27. The adjustment of the block 81 is effected by a thumb screw 99 which engages the slot of the support 98. The block 81 and the shoe 97, therefore, are capable of adjustment together, and by means of the screw 99 the block 81 and the shoe 97 may be held at any desired point of adjustment along the support 98, thereby providing for engagement of the shoe 97 with the bell-crank 88, as well as engagement of the block 81 with the lever 82, at different points on the carriage 27. The lower end of the contact shoe 97 is deflected so that the same will have a rolling contact with the anti-friction roller 94, and at the same time this deflected end will swing the bell-crank lever 88 on its pivot until the roller 94 has cleared the deflected end, whereupon the roller 94 will travel along the vertical side of said shoe 97, thereby holding the clutch members 79 and 80 in engaged relation until the shoe 97 has cleared the bell-crank lever. At this time the pull of the spring 90 draws the lower end of the shifting lever 86 inwardly and releases the clutch member 79 from engagement with the member 80. When this release takes place, and the filled bag has been

removed from the shelf 29 of the carriage 27, the counterweights 37 move downwardly in the guides 38, thereby elevating the carriage to its position in proximity to the discharge nozzle 26 for the support of the new empty bag which has been placed thereon. As the carriage 27 rises the upper end of the contact shoe 97 will engage the finger 93, swinging the latter upwardly so that said 5 shoe may clear the bell-crank 88, and this permits restoration of the parts to their normal position without liability of breakage of the bell-crank 88 or the appurtenant parts of the mechanism employed for shifting the 10 clutch member 79.

It is desirable that the upward movement of the carriage 27 should be limited, and for this purpose a pair of inwardly deflected stops 100 is employed. One of these stops 20 is mounted on each of the frame members 10, the upper end of each stop terminating in an over-hanging head 101. These heads 101 are contacted by rearwardly-extending abutments 102 carried by the carriage 27, 25 whereby the upward movement of the carriage 27 is checked.

To cushion the carriage 27 as it comes to rest on its downward movement a series of elastic buffers 103 are supported in the lower 30 end of the frame in the path of said carriage, the lower end of the carriage contacting with these buffers and thereby eliminating shock to the carriage.

From the foregoing the operation of the 35 herein described machine will be understood, and briefly described is as follows: The bag or sack to be filled is placed on the discharge nozzle 26 so that the bottom thereof will be adjacent to the lower end of said nozzle. At 40 this time the shelf 29 of the bag supporting carriage 27 is in its elevated position, and the bag is held against downward displacement from the nozzle 26. The connecting rod 46 now being forced downwardly, by 45 downward pressure applied to the operating handle 44 or to the treadle frame 49, the actuating lever 48 operates the clutch mechanism 22 to establish driving relation between the shaft 18 and the packing shaft 23. In 50 the movement of the lever 44 just mentioned it is swung past a dead center and to the dotted line position shown in Fig. 1, thereby holding down the connecting rod 46 and locking the clutch mechanism 22 in its 55 operative power-transmitting position. This sets in rotation the packing augers 24, and the flour is thereby forced downwardly through the nozzle 26 into the bag or sack thereon. The flour thus becomes compacted 60 in the bag or sack, and as the latter is filled the shelf 29 is forced downwardly against the counterbalancing effect of the counterweights 38, as well as the resisting action of the control shaft 32 due to the braking action 65 of the shoes 54 and 55 now exerted on

the friction wheel 53. It will be remembered that on the downward movement of the rod 46 the lever 64 has been swung downwardly also by the yoke 66 and connecting rod 67 which extend between said lever and said rod 46. When the required quantity of contents has been placed in the bag or sack the block 81 contacts with and actuates the lever 82 to the full-line position of Fig. 1, and this throws the rod 46 upwardly in order to disconnect, by proper actuation of the clutch mechanism 22, the packing shaft 23 from its driving relation with the shaft 18. As the spring 72 is now pulling the lever 64 upwardly, the brake 80 shoes 54 and 55 are released from the wheel 53 so that resistance of the shoes 54 and 55 to rotation of the control shaft 32 is removed. The contact shoe 97 now being in engagement with the bell-crank lever 88, 85 the continued downward movement of the carriage 27 causes the bell-crank lever 88 to be swung on its pivot, and the shifting lever 86 to be swung outwardly. This engages the clutch member 79 with the clutch member 80, imparting accelerated movement to 90 said control shaft, resulting in a quick downward movement of the carriage 27 for the remainder of its travel until shoe 97 rides off lever 88, and thereby placing the 95 filled bag or sack in position conveniently to be removed from the shelf 29. When the weight of the filled bag or sack is freed from the shelf 29 the counterweights 38 promptly act to raise the carriage 27 to its elevated 100 position and for supporting a new empty bag or sack which has been placed on the discharge nozzle 26. The return upward movement of the carriage 27, under influence of the counterweights 38, is, of course, 105 rapid, but just prior to the carriage 27 reaching the limit of its upward movement the brake shoes 54 and 55 are applied to the wheel 53, and the upward movement of the carriage 27 is thus checked. This application 110 of the brake shoes is due to the contact of the tappet arm 75 with the inner end of the lever 73 on the reverse rotation of the sprocket wheel 34 due to the descent of the weights 38. When this contact of the tappet 115 75 and the lever 73 takes place said lever is rocked on its pivot, its outer end is depressed, and this depresses the lever 64 so as to swing the brake shoes 54 and 55 into engagement with the wheel 53. The cycle of 120 operations just described is repeated with each bag or sack, it being understood that when the packing shaft 23 is at rest there is no discharge of the flour from the nozzle 26.

Various sizes of bags may be employed, 125 and the adjustability of the parts herein described permits the machine to fill the respective weights of bags with the varying amounts of the flour or other material being packed. Under these adjustments the ac- 130

tuation of the machine is such that approximately the exact weight will be introduced to the different sizes of the bags, and this avoids the necessity of incorporating in the 5 machine weighing mechanism for the determination of the precise weight of the contents of the bags. As the latter are removed in their filled condition from the machine they may be placed upon a scale and the required amount of flour placed in the bags or 10 sacks or taken therefrom to give the precise weight of the contents which the bags or sacks are to contain. In the actual working 15 of the machine herein described it is found that but slight variation in the weight of the contents occurs, and this is compensated for at the time that the actual weight of the filled bag is determined.

The machine may be equipped with a registering counter 104 for indicating the number of bags filled by the machine when in 20 operation. This counter may be of any approved construction and is actuated from the bag supporting carriage 27 to register 25 each filled bag by suitable tripping devices interposed between said carriage and the counter.

I claim:

1. In a machine of the class described, the 30 combination with feeding means, of a receptacle support movable towards and away from the same, a control shaft, operative connections between said control shaft and said support, said control shaft operating 35 through said connections to control positively the receptacle support in its movement both to and from the feeding means, and actuating shaft, a clutch for rendering the actuating shaft effective on the control shaft, and means operable by the receptacle support for operating the clutch.

2. In a machine of the class described, in 40 combination, feeding means, a support movable toward and from the same, a control shaft operably connected with the support, an actuating shaft, a clutch for connecting the actuating shaft to the control shaft, braking means effective on the control shaft, and means operable by the support for operating the clutch and the braking means.

3. In a machine of the class described, the

combination with feeding means, of a receptacle support movable towards and away from the same, a control shaft, operative connections between said control shaft and said support, said control shaft operating 55 through said connections to control positively the receptacle support in its movement both to and from the feeding means, driving means for actuating the control shaft, and means operable by the support to control the effectiveness of the driving means on the control shaft.

4. In a machine of the class described, the combination with feeding means, of a receptacle support movable towards and away from the same, a control shaft, operative connections between said control shaft and said support, said control shaft operating 60 through said connections to control positively the receptacle support in its movement both to and from the feeding means, said operative connections between the control shaft and said support serving also to determine the direction of movement of one 65 by the direction of movement of the other, drive mechanism, a clutch controlling the effectiveness of the drive mechanism on the control shaft, and means operable by the support for operating the clutch.

5. In a machine of the class described, in combination, feeding means, a movable receptacle support, a control shaft, driving connections between said shaft and the support whereby the direction of movement of 70 one is determined by the direction of movement of the other, drive mechanism, a clutch controlling the effectiveness of the drive mechanism on the control shaft, means operable by the support for operating the clutch, braking mechanism for governing movement of the control shaft, and means operable by the support for controlling effectiveness of the braking means.

In testimony whereof I have hereunto 75 subscribed my name in the presence of two subscribing witnesses.

HENRY O'B. HARDING.
